UNITED STATES PATENT OFFICE

HARVEY W. BECK AND ROBERT M. BELL, OF DANVILLE, PENNSYLVANIA

SINGLE NEEDLE JOINING FOLDER

Application filed April 3, 1931. Serial No. 527,592.

This invention relates to an attachment for sewing machines, the general object of the invention being to provide means for folding over the edges of two pieces of material and guiding an edge of a third piece between the folded over edges so that the needle of a single needle sewing machine can sew the pieces together, the invention being mainly designed for joining the front and rear portions of a shirt to the yokes at the shoulders of the shirt.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a top plan view of the attachment.

Figure 2 is a view looking toward the outer edge thereof.

Figure 3 is an end view showing in dotted lines the material passing through the device.

Figure 4 is a detail view showing how the three pieces of material are positioned by the device.

Figure 5 is a detail view showing how the material is arranged when engaged by the needle.

In this drawing, the numeral 1 indicates a plate which is provided with a pair of oblong openings 2 adjacent one corner thereof so that the plate can be fastened by set screws or the like to a part of a single needle sewing machine. Intermediate the ends of the plate is an upwardly curved portion 3 having a top part which slopes downwardly from the far edge of the plate to the inner edge or that edge which is nearest the needle.

A vertical part 4 is connected to the edge of the horizontal part and has a substantially horizontal flange 5 extending inwardly from its lower edge, the flange gradually increasing in width from the outer end of the part 4 to its inner end and this flange is spaced from

the horizontal part of the portion 3. A plate 6 has its inner end bent into a loop with its extremity connected with the top part of the portion 4. A substantially U shaped part 7 has one edge connected with the part 4 and this part 7 loops around the loop part of the portion 6. Thus the horizontal part of the portion 3 and the flange 5 forms a space which will form a loop a in a piece of material A when said piece A passes over the right hand part of the plate 1 and the space between the loop part of the member 6 and the part 7 will form a loop a' in a piece of material A' as the same passes over the part 6. The piece of material B has one edge guided in the space formed by the horizontal part of the portion 3 and the lower part of the portion 7 and as all of these spaces slope downwardly toward the needle side of the device, the looped edges of the pieces A and A' and an edge of the piece B are brought together, as shown in Figure 5, so that the needle of the machine can sew the edges together.

As before stated, the machine is mainly designed for sewing the front and rear portions of a shirt to the shoulder yokes thereof.

Tongues 8 are placed on the needle side of the device, one forming an extension of the end of the flange 5 and the other forming an extension of the end of the lower part of the folded portion of the plate 6, for guiding the material to the needle.

It is thought from the foregoing description that the advantages and novel features of the invention will be readily apparent.

It is to be understood that changes may be made in the construction and in the combination and arrangement of the several parts, provided that such changes fall within the scope of the appended claim.

What we claim is:

A folder of the character described comprising a plate formed with an upwardly and laterally curved portion inclined transversely of said plate, a vertical portion rising from the outer edge of said first named portion and having a flange extending inwardly spaced below the upwardly and laterally curved portion, the flange being gradually increased in width from end to end, a plate having a loop

joined with the uppermost of said second named portion, and a loop extended from the second named portion and following the loop of the plate and spaced an equidistance therefrom, said flange, loops and plate being inclined correspondingly to the incline of the upwardly and laterally curved portion.

In testimony whereof we affix our signatures.
